SIGNALING APPARATUS FOR GRADE CROSSINGS

Ernst Wilckens, Berlin-Sudende, Germany, assignor to Julius Pintsch Kommanditgesellschaft, Berlin, Germany

Application August 26, 1937, Serial No. 160,972
In Germany April 2, 1937

10 Claims. (Cl. 246—125)

Signaling apparatus, intended for ensuring the safety of traffic, are working in many cases with two different signals. Thus, for instance, the administration of railway traffic works with green light as "safe" light and red light as "block" light. In signaling installations serving for regulating the traffic at crossings and railway tracks, a white flash light is provided for indicating clear way, as well as for showing that a signaling device has been provided at this point for the purpose of safeguarding the crossing. Red flash light is to stop the road traffic, because the approach of a railway train is indicated thereby.

Signaling installations of this nature are fed either by means of storage batteries or primary batteries. They are also connected immediately to D. C. and A. C. supplies, in many cases in conjunction with the interpolation of buffer batteries.

In installations, which are connected immediately to a long distance-, municipal- or station-circuit and which have no current reserve to provide for breakdown or failure of this circuit, the two signals will not work so that no signaling can take place. This indicates to the road user that the installation has broken down and that he must not continue his way until he has satisfied himself that the way is clear for traffic.

So far two arrangements have been provided in connection with the re-appearance of the circuit voltage. The first arrangement switches in the ordinary operating or "safe" light signal. The second arrangement provides the switching in of the warning or blocking signal. In installations, in which the interruption of the circuit may possibly cause a wrong signal being shown after return of the operating voltage, it has so far been decided, for reasons of safety, to cause the warning or blocking signal to light up again in any case. This, it is true, represents in the first instance, a safeguarding of the traffic but, on the other hand, it causes the grade crossing to be blocked for an unnecessarily long period. The result might be, particularly in signaling installations for grade crossings, that the road users may get used to the fact that, in spite of blocking signal, no train is passing; they will, in consequence thereof, lose the respect for these warning signals, so that the purpose of the safeguarding device loses in importance.

According to the present invention an arrangement is provided whereby when the current is again supplied to the system after an interruption, the signal circuit will not be immedi-

ately energized if there is a train on that section of the track controlling the signals but when the track becomes clear of trains the signal circuit will be restored to normal condition. The special switching device thus has, in some sort, the effect that the blocking section or warning track will be examined, partly or wholly, as to whether there are train axles to be met with. If this is not the case, the line will be rendered clear or, 10 in other words, the signals will be switched in again. In connection herewith the arrangement is of such nature that after the return of the voltage, but prior to the energizing of the circuit controlling the signals, a train passing 15 through the block section automatically causes the signals to be switched in again through the medium of the special switch system.

According to a preferred example of performance of the present invention the special switch 20 system comprises a time-relay which is actuated by the returning circuit voltage and which, after a certain time, causes the signals to be switched in. The period of operation of the time relay, after which the signals are switched in again, 25 suitably exceeds the longest period of passage of a train through the entire or through half the block section. This will ensure that a train which is in the block section or at the beginning or end of the latter at the moment at which the circuit voltage returns, will have left the block section again before the signals are switched in again.

According to a further example of performance of the present invention, the special switch system 30 comprises a relay or a relay set which is dependent, on the one hand, on the circuit voltage and, on the other hand, on the switching state of the signaling apparatus or installation, in such a manner that it is actuated on the return of the circuit voltage and thereby causes the signals to be switched in again, provided, that the signaling apparatus or installation is in a switching state which corresponds to the blocking section, or its beginning or end, being clear. 40 Thereby it will, furthermore, be attained that the change from the dark position of the signals will only be effected when there is no train 45 within the installation.

Moreover, also in connection with the first example of performance, the time relay can be made to be dependent, apart from the circuit voltage, also on the switching state of the signaling apparatus or installation, particularly in such a manner that the time relay, already in 50 operation when a train is entering the block sec-

tion, is caused to assume its final or end position or is rendered ineffective or impeded in its operation and, if necessary, continues in operation, after the train has left the blocking section.

With the aid of the annexed circuit diagram a supervisory or controlling plant has been illustrated.

Figure 1 is an electrical diagram of a signal circuit embodying the invention;

Fig. 1a is an electrical diagram of an alternative arrangement of the time relay 6 and certain related switches;

Fig. 2 is a diagrammatic illustration indicating the relative times of closing the contacts 61 and 62 during the rotation of the cam controlling the same;

Fig. 2a is a similar diagrammatic illustration indicating the relative times of closing the contacts 41 to 44; and

Fig. 3 is an electrical diagram showing an alternative embodiment of the invention.

In the example of performance the installation is equipped with two tripping elements K1 and K2 at the ends of the block section adapted to be actuated by a passing train to open the electric circuit and a short insulated bar A at the crossing, two track relays 1 and 2 being connected to these switching means. In addition thereto the installation is equipped with two auxiliary relays 3 and 4 the second of which is a motor driven time relay, a circuit pilot or control relay 5 and the motor driven time relay 6. The two contacts 61 and 62 of the relay 6 are controlled by the cams 6a and 6b of said relay. When the relay is in the position of rest in which it always stops after operation, both contacts are open. Contact 61 serves to maintain the circuit of the relay through conductors 601a, 601, 602, 603a and 603 and is, for this reason, closed during the entire period of operation. Contact 62 will be closed only temporarily at the end of the period of operation, simultaneously establishing the circuit of the relay 5 through conductors 504 and 503.

General description

In the arrangement of Fig. 1 when the system is in normal operative condition, that is to say with the current on and no train within the block between the tripping elements K1 and K2 the several switches or contacts will be in the position shown in Fig. 1.

In this normal condition of the various relays of the system, the warning signal R is off and the free signal W is on.

Relays 1 and 5 are energized each holding several switch contacts in the position shown against the action of gravity. Relays 2 and 3 are de-energized.

The time relay 4, which operates when energized to rotate its cams 4a, 4b, 4c and 4d through one complete rotation always stopping with the cam followers in the raised position shown, is not energized and stands in arrested position.

Time relay 6, which also operates when energized to rotate its cams 6a and 6b through one complete rotation stopping always with the followers in the depressed position shown, also stands in arrested position. This relay serves no purpose when the system operates normally but when the current through accident or otherwise is shut off and again supplied to the line, it operates to prevent the operation of the

system for a period of time sufficient to permit a train within the block at the moment when the current is turned on to pass through the block.

A passing train travelling from left to right in Fig. 1 will first trip the tripping element K1 which will open the circuit to de-energize relay 1 and close a short circuit to retain relay 1 in de-energized position until the train engages the insulated rail section A. The de-energizing of the relay 1 will reverse the signals to turn on the warning or danger signal R and to turn off the free signal W. The train, continuing, will engage the insulated rail section A and while it is on said section the relay 2 is energized and also the relay 3 is energized through the action of relay 2. Relay 1 is re-energized through the action of relay 2. When, as the train passes, the relay 2 is de-energized the warning signal will be turned off and the free signal will be turned on. At this moment the relay 3 is still energized and therefore not in normal de-energized condition. This relay is a safety device and serves the purpose of preventing the energizing of relay 4 when relay 1 is de-energized by actuation of tripping element K1 but permits energizing of relay 4 when relay 1 is de-energized by actuation of tripping element K2.

Relay 1 is de-energized during the passing of the train over the tripping element K2 and is then restored to energized condition. When de-energized it starts motor relay 4.

Relay 3 is now de-energized and relay 4 will continue to operate until its cams 4a, 4b, 4c and 4d have completed one rotation and then it will stop with the cams in the position shown in Fig. 1 lifting the several controlled elements. The circuit is now in the normal position as before the train entered the block.

Relays 5 and 6 have not been affected.

Suppose the current fails in the line and is again restored. Arrangement is provided in accordance with the present invention whereby improper operation of the signals such as might occur if the current were restored while a train was in the block between the tripping elements K1 and K2.

When the current fails in the line, relay 1 is de-energized but it is connected in circuit ready to be energized if a train enters the block. Relay 2 stands de-energized. Relay 3 stands de-energized and with its circuit open. Relay 5 is de-energized and its circuit is open. Time relays 4 and 6 stand in normal arrested position.

When the current is turned on, relay 1 will be energized. Relay 6 will be energized to rotate its cams 6a and 6b through one complete rotation and then stop. Relay 6 after a predetermined period of time will cause relay 5 to be energized. The time delay is sufficient to provide ample time for a train already in the block to pass through the block before relay 5 is energized. After relay 5 is energized all parts of the circuit are in normal operative position, as shown in Fig. 1. It is to be noted that relays 2, 3 and 4 are not affected by the restoring of the current.

If a train enters the block after the time relay 6 has started operation, but before it has caused operation of relay 5, then relay 5 will be energized upon operation of a tripping element K1 and the whole system will then be in normal operating condition ready to cause proper control of the warning and free signals as usual.

The function of the several relays will be clear from the description found herein. Relay 6, for example, serves as its main purpose to prevent

actuation of relay 5 and therefore restoration of the system to normal position while there is a train in the block. Relay 5 in its off position prevents operation of several circuits at an improper time. Relays 3 and 4 cooperate to prevent a short circuiting of relay 1 when the circuit is not in normal condition, thereby preventing an improper operation.

In connection with a proper operation the arrangement functions as follows:

The interruption of the contact, say K1 by the approaching train, causes the relay 1 to be de-energized by opening the circuit 101, 102, 103. In connection herewith contact 12 of this relay produces a short circuit through conductors 106, 105, switch 42, conductor 104, switch 52, switch 24 and conductor 104 for its relay which thus, in the first instance, remains in the release position, whilst contact 11 switches the "free" signal W off and the warning signal R on. The circuit of the free signal W includes conductor 113, switch 21, conductors 114, 114a, 115, switch 55, and conductors 116 and 117. The circuit of the warning signal R includes conductors 112a, 118, 118a, switch 41, and conductor 119. This condition will remain, until the first train axle causes the relay 2 to respond by coming in contact with the insulated bar or rail A. This causes the relay 3 to be switched in by contact 22 and the short circuit of the relay 1 opened by means of contact 24, so that the relay 1 can now respond again, in connection with which the contact 21 is instrumental in causing the warning signal R to remain switched on. The contact 22 closes the circuit through conductors 303, 302, 301 and 307 to the positive terminal. The relay 3 is already connected to the negative terminal through conductor 304, switch 54 and conductors 305 and 117. Contact 21 engaging contact 21b closes the circuit of the warning signal R through conductors 118b, 114 and 114a, switch 11, conductor 115, switch 55 and conductors 116 and 117 thereby supplying current to the warning signal R. When the last train axle leaves the insulated rail A, the relay 2 is released or dropped, so that the contact 21 switches over from the warning signal R to the "free" signal W by moving from contact 21b to contact 21a. The relay 3 remains pulled up via its own contact 32 and contact 43 in spite of the interruption of contact 22. The holding circuit involved includes conductor 310, switch 32, conductor 306, switch 43 and conductor 301 which connect one side of the relay 3 to the positive terminal. When the vacating train passes over the rail contact K2, the relay 1 drops again and switches in the time relay 4 (see Fig. 2a) by means of contact 13, the time relay producing for itself, for a period determined by its adjustment, a holding circuit via its contact 43, conductors 301 and 406 and causing the "safe" signal W to remain switched in by means of contact 41 by closing the circuit through contact 41b, conductors 114b, 114, switch 21 and conductor 113 on the one hand and through conductor 119, switch 11, conductor 115, switch 55 and conductors 116 and 117 on the other hand. The changing over of contact 43 to contact 43a prepares the release of relay 3 which is still pulled up via the contact 14. Release is prepared because contact 32 is now connected to the positive terminal only through conductor 309, switch 14 and conductor 308. The connection through conductors 306, 302 and 301, is broken by the movement of contact 43 from contact 43b. After the train has passed over the contact K2, the relay 1 will

respond again in the first instance. After a certain time, also the time relay 4 will be caused to stop again as contact 43 opens the holding circuit through conductors 301 and 406, so that the normal position of the installation will be restored again. If the relay 4 should complete one rotation and contact 43 open its holding circuit before the train has passed over the contacts K2, it can, because the relay 3 is still pulled up via the contact 14, respond again, in order to drop once more after a certain time and to restore the original condition of circuits controlled by it.

The relay 2, connected to the insulated rail A, can also be connected in series with the relay 1 in the current loop and can be so designed that, when the contacts K1, K2 are interrupted, remains pulled up via resistances shunted across the contacts and only drops, when the insulating rail is passed over or the cable is fractured in the current loop, so that in this way a permanent control of the closed circuit current loop is ensured.

If the voltage of the current source S fails whilst the installation is in any position, the closed circuit current relay 5 will release all contact elements controlled by it. It should be noted, that thereby the circuit of the relay 5, via which the latter is fed during normal operation, is interrupted by its own contact 51 of the relay 5. By means of three further contacts 52, 54, 55 other circuits are opened. Contact 52 opens the short circuit of relay 1 which short circuit includes contacts 12, 42, 53, 24 and conductors 106, 105, 104b, 104a and 104. Contact 54 opens the circuit of relay 3 by disconnecting conductors 304 and 305. Contact 55 opens the circuit 115, 116 of signal lamps W and R. At the same time contact 53 prepares the holding circuit including the conductors and switches 203, 53, 204, 16, 205 for relay 2. This circuit is open at 16 but ready for closing when relay 1 is energized. As soon now as the voltage returns to the feed circuit, the relay 1 is fed with current and responds. This will cause at the contact 16 the prepared circuit to be closed for the relay 2 which thus also pulls up. In addition thereto the time relay 6 will respond via contact 56 and conductors 60 and 601 and thereby be started, in connection with which it soon closes at the contact 61 a holding circuit through conductors 601a and 603. After a prolonged period contact 62 is closed and the relay 5 switched in thereby through conductors 504, 501. The responding relay 5 produces together with the contact 51 a holding circuit and also leads back into their normal conditions all other circuits controlled by it, particularly closing the circuit for the signal lamps W, R, through contacts 55, 11, 21 and 41 and conductors 115, 114, 113, 118 and 119.

If, prior to the complete run-down of the time motor relay 6, a train passes into the block section, e. g. via contact K1, the relay 1 will, as usual, drop. This will at the contact 15 cause the operating circuit of the relay 5 to be closed already in advance and the release of the installation prepared already at that moment. The circuit includes conductor 508, contact 15, conductor 507, contact 25, conductor 506, contact 44 and conductors 505 and 501. Note that contact 25 is still held closed by relay 2. As relay 5 is thus energized the holding circuit of relay 2 is opened at contact 53 and the complete system is in normal operation. The fact that motor relay 6 is still running is immaterial.

Fig. 1a represents another modus of connection

of the time relay 6, in which the latter is also rendered dependent on a relay of the signal connection, i. e. the motor time relay 4, by means of the contact 45. This will cause the time relay 6 to be temporarily arrested when the relay 4 responds.

In the arrangements described so far one relay 5 and one relay 6 each were provided for the restoration of the signal circuits and for the retardation of the restoration. According to a further development of the present invention an essential simplification can be attained by designing the release relay itself as a time switching relay. For this purpose rotary time switching devices, cam discs and the like, can be used. In this case, however, an arrangement of resistances and condensers proves of special interest, in connection with which the advantage is attained, that intermediate connections of whatever description of the time switching device will be impossible. In connection with the revolving contact-paths it can, as a matter of fact, happen, that the time switching device, at a circuit interruption, will find itself in an intermediate position and permanently remains in the latter. In a condenser, however, the charge of the latter will escape after a short time via the connected resistances or also via its own leaking resistance automatically, so that the arrangement always permits of utilizing the full charging time. Apart therefrom, however, condensers are considerably cheaper than revolving time switching devices, so that the price for a release arrangement of the signaling plant can be reduced to a fraction.

A circuit arrangement of this nature is illustrated in Fig. 3. The connection of the track relays is identical with that of the examples previously referred to. If the source of power fails, the relay 5, which is designed as closed circuit current relay, also drops and opens its contact 51, so that it cannot immediately pull up again at circuit return. In connection therewith the relay 5 produces an interruption with the aid of the contact 52 in the shorting circuit of the relay 1 and prevents, by means of the contact 54 the auxiliary relay 3 from responding, and by contact 55 opens the signal circuit. The contact 52 is characterized by the effect, (because it is open) that at the return of power in the line the relay 1 can pull up at once and simultaneously cause its contact 15 to change from its position 15b into the position 15a. This will cause current to flow via the resistance W_1 through the relay 5 by conductors 511 and 512, in connection with which, however, a corresponding retardation of the pull-up of the relay 5 will be caused by means of the condenser C and the resistance W_2 , which are located in circuit with the contact 56 by conductor 604, closed at that time, and in parallel with the relay 5. The contact 16 will now, through conductors 204, 203 and contact 53, furthermore, cause the relay 2 to be energized which, however, will occur before the relay 5 acts. When, after its retardation, relay 5 has definitely pulled up, the contact 53 will open the circuit of the relay 2 and cause the latter to drop again. If now, at the moment of the circuit return while relay 2 is energized a train passes over one of the switching-in contacts K_1 or K_2 , the dropping of the relay 1 will cause current to be immediately fed to the relay 5 via conductor 509, contact 25, conductor 506, contact 44, conductor 510, contacts 15b, 15 and conductor 511 whereby the

retarding effect of the condenser C will be avoided. The relay 5 will then pull up without any retardation. For the purpose of ensuring as extensive a retardation as possible, the relay 5 should suitably be of such dimensions, that it pulls up closely below the operating voltage, in connection with which the resistance W_1 is correspondingly small, e. g. 5-10% of the relay resistance. The resistance W_2 must be so chosen, that it is neither too great nor too small. The optimum value is best determined by test. Naturally, C should be as great as possible, but it has been ascertained, that retardations of from 1 to 2 minutes, as they are being considered for the purposes under consideration, are attainable even in conjunction with moderate condenser values.

What I claim, is:

1. In combination a stretch of railway track including a section intersected by a highway, a traffic signal adjacent the highway, an electrical circuit including switch means controlling said signal, train operated tripping elements positioned to be operated by a train passing through said section arranged to control the switch means of said electrical circuit, a current source from which said electrical circuit receives power, a relay normally energized from the current source to maintain the switch means of said electrical circuit in operative condition, a safety control circuit including switch control means normally energized from the current source to maintain said circuit in operative condition, the switch control means of the safety control circuit including a switch and means to open said switch upon failure of the voltage in the current source, and means for restoring current to said safety control circuit upon restoration of the voltage in the current source including a time delay relay, together with an auxiliary circuit including control means operated by the train operated tripping element first engaged by a train entering the section to immediately re-energize said control circuit upon entrance of a train into the section.

2. In combination a stretch of railway track including a section intersected by a highway, traffic signals including warning and free signals, signal circuits including switch means arranged to control said traffic signals, a current source from which said circuits are energized, a control relay normally receiving energy from said current source, switches operated by said relay arranged when the relay is energized to control said signal circuits to maintain the same in operative condition and arranged when said relay is de-energized to maintain said signal circuits in inoperative condition, switch means to open the circuit from the current source to said control relay automatically operative upon failure of voltage in the current source, switch means for re-connecting said control relay to the current source upon restoration of voltage in the current source including a time delay relay, and auxiliary means actuated in response to the movement of a train into the section cooperating with said last mentioned means for re-connecting the control relay independently of the time delay relay.

3. In combination, a stretch of railway track including a section intersected by a highway, highway crossing signals including warning and free signals located at the intersection, a current source for supplying current to said signals, means for controlling the supply of current from said current source to said signals including a

safety control relay, said control relay being arranged to be de-energized upon failure of voltage in the current source, and means for causing said control relay to be re-energized upon restoration of voltage in the current source including a time delay relay.

4. In combination, a stretch of railway track including a section intersected by a highway, highway crossing signals including warning and free signals located at the intersection, a current source for supplying current to said signals, means for controlling the supply of current from said current source to said signals including a safety control relay, said control relay being arranged to be de-energized upon failure of voltage in the current source, means for causing said control relay to be re-energized upon restoration of voltage in the current source including a time delay relay, and means to re-energize said control relay independently of the time delay relay including a train operated switch whereby the switches may be restored to position during operation of the time delay relay.

5. In combination, a stretch of railway track including a section intersected by a highway, highway crossing signals including warning and free signals located at the intersection, signal control circuits for said warning and free signals including a train operated switch positioned to be operated by an approaching train connected to cause energizing of said warning signal and de-energizing of said free signal, a safety control switch connecting the current supply and the signal control circuits, means for opening said switch upon failure of current in the current supply, and means actuated by said train operated switch to cause closing of said safety control switch.

6. In combination, a stretch of railway track including a section intersected by a highway, highway crossing signals including warning and free signals located at the intersection, electrical circuits for controlling said warning and free signals including a safety control relay and switches controlled thereby for supplying current from the current source to the control circuits, said relay having a holding circuit, and means for re-energizing said relay upon restoration of voltage in the current supply after failure thereof including a time delay relay and electrical connections to said current source controlled thereby.

7. In combination, a stretch of railway track including a section intersected by a highway, highway crossing signals including warning and free signals located at the intersection, means normally controlling the warning and free signals including a train operated means arranged to be operated by an approaching train to energize the warning and de-energize the free signal and a train operated means arranged to be operated by a train passing the crossing to energize the free signal and de-energize the warning signal, a source of current from which said signals are energized, safety control means associated with said source of current and said signals to prevent operation of said signals under predetermined conditions, means for restoring said safety control means to normal condition to permit operation of the signals as controlled by the train operated means comprising a time delay relay arranged to be set in operation by restoration

of the voltage in the current source after an interruption, and means arranged to be set in operation by operation of the first mentioned train operated means and operative to restore the safety control means to normal condition independently of the time delay relay.

8. In combination a stretch of railway track including a section intersected by a highway, a highway crossing signal located at the intersection, train operated circuit controllers, relays operatively connected to the circuit controllers to be controlled thereby, means controlled by said relays for operating the signal, means for supplying current to the relays from a current supply, means for supplying current to the crossing signal including a switch, means for closing said switch after an interruption of the supply circuit has taken place and the current supply voltage has been restored including a time delay relay, and means operated by the train operated circuit controllers for closing the circuit between the current supply and the crossing signal independently of the time delay relay.

9. In combination, a stretch of railway track including a section intersected by a highway, highway crossing signals including warning and free signals located at the intersection, a current source for supplying current to said signals, means for controlling the supply of current from said current source to said signals including a safety control relay, said control relay being arranged to be deenergized upon failure of voltage in the current source, means for causing said control relay to be re-energized upon restoration of voltage in the current source including a time delay relay, means controlled by a train approaching the intersection for connecting the warning signal to the current source and disconnecting the free signal, and means controlled by a train beyond the intersection for connecting the free signal to the current source and disconnecting the warning signal including a time delay relay which temporarily closes an electrical connection between the current source and the free signal.

10. In combination, a stretch of railway track including a section intersected by a highway, highway crossing signals including warning and free signals located at the intersection, a current source for supplying current to said signals, means for controlling the supply of current from said current source to said signals including a safety control relay, said control relay being arranged to be de-energized upon failure of voltage in the current source, means for causing said control relay to be re-energized upon restoration of voltage in the current source including a time delay relay, means controlled by a train approaching the intersection for connecting the warning signal to the current source and disconnecting the free signal, and means controlled by a train beyond the intersection for connecting the free signal to the current source and disconnecting the warning signal including a train operated switch, a time delay relay, a circuit controlled by the time delay relay for temporarily connecting the free signal to the source of power, and a train operated device for energizing said time delay relay.

ERNST WILCKENS.
